(57) **CLAIM**

The ornamental design for a personal medical dispenser, as shown and described.

DESCRIPTION

FIG. 1 is a perspective front view of a personal medical dispenser, shown with the removable tray;

FIG. 2 is a front elevation view shown without the removable tray;

FIG. 3 is a rear elevation view thereof;

FIG. 4 is a left side elevation view thereof;

FIG. 5 is a right side elevation view thereof;

FIG. 6 is a top plan view shown with the removable tray;

FIG. 7 is a bottom plan view thereof;

FIG. 8 is a cross-sectional view shown without the removable tray, taken along line 8-8 of FIG. 6; and,

FIG. 9 is an exploded perspective view thereof.

The broken lines depict portions of the article that form no part of the claimed design.
